LIMITED TRAVEL DRAFT GEAR
CONSTRUCTION

Hubert L. Spence, East Cleveland, Ohio, assignor
to National Malleable and Steel Castings Com-
pany, Cleveland, Ohio, a corporation of Ohio

Application October 27, 1931, Serial No. 571,311

3 Claims. (Cl. 213—56)

This invention relates to limited travel draft gear constructions, and more particularly to means whereby the draft gear may be compressed in buff a greater amount than is usual and compressed in pull a lesser amount than in buff.

An object of the invention is to provide novel and improved means of the type referred to, which shall be of simple construction, inexpensive to manufacture, easy to assemble and durable in service. Another object is the provision of a draft gear construction wherein greater compression in buff than in pull is effectively attained without interference with or complication of the spring construction and without taking up space which would otherwise be available for springs. Other features and advantages of the invention will become apparent as the description proceeds.

A preferred embodiment of my invention will now be described in connection with the accompanying drawings wherein Fig. 1 is a plan view, partly in section of draft mechanism in which the invention is incorporated. Fig. 2 is an enlarged section taken on the line 2—2 of Fig. 1. Fig. 3 is an enlarged section taken on the line 3—3 of Fig. 4. Fig. 4 is a vertical section showing the construction illustrated in Fig. 1. Fig. 5 is an enlarged perspective of the yoke.

For purposes of illustration, the construction is shown as including a yoke of the vertical type, to the forward end of which is pivoted a swiveling coupler. However, it will be appreciated that the invention is susceptible of embodiment in connection with other types of yoke and coupler. Shown at A are car sills joined at their forward ends by striking casting B and at their rearward ends by back stop casting C. A friction draft gear of suitable construction is shown as comprising a housing member 1, into the forward end of which there telescopes a wedge or follower 2. Shock absorbing or cushioning mechanism of any suitable or convenient type may be interposed between said wedge and housing members, the gear here shown for purposes of illustration being of the same type as that disclosed in the pending application of Ernest H. Schmidt and Hubert L. Spence, Serial No. 319,064, filed November 13, 1928, Patent No. 1,913,414, June 13, 1933. Springs 3 included in said shock absorbing mechanism are shown within the housing 1. The rear end of housing 1 may abut against projections 4 on the back stop casting, while the follower 2 is adapted to abut against draft lugs 5 secured to the sills. A yoke 6 is shown as extending above and below the draft gear and having a portion 6—a for abut-

ment against the rear of the draft gear housing 1, and a portion 6—b to which is pivoted at 7 the shank 8 of the coupler 9 in a known manner.

In order to provide for, say 4" travel of the gear in buff the back stop casting is cut away as at 10 an amount ample for the desired travel and sufficient clearance. This increased travel of the gear in buff is particularly desirable inasmuch as buffing shocks are ordinarily considerably greater than those in pull. On the other hand, it is not desirable to have this amount of travel in pull, especially in long trains. However, the varied and conflicting requirements of a draft gear construction make it difficult to provide for such lesser travel in pull without complicating the construction of the draft gear or introducing structural weaknesses.

I have found that by providing the yoke with projections 6—c and by extending the draft lugs 5 upwardly and downwardly, as at 5—a, sufficiently to engage the projections on the yoke, the travel of the gear in pull is simply and effectively limited to the desired amount. It is advantageous to provide lateral projections 6—c at either side of the yoke and on both its upper and lower portions and to provide corresponding extensions on the lugs 5 for each of these projections. For example, the distance between each projection 6—c and the corresponding draft lug may desirably be 2½". That is, the yoke and lugs will go solid after the yoke has moved forward 2½", while the housing section 2 is permitted to travel 4" in buff before going solid against the housing section 1. The projections on the yoke conveniently pass above and below the housing section 2, and contact directly with the extensions of the draft lugs which are secured to the sills.

It may be noted that in this construction no extra room is required for the parts which limit the travel of the gear in pull, the projections 6—c and extensions 5—a being accommodated in the space which is available without modification of standard sill and draft gear constructions. By reason of this compact construction there is room for a draft gear of increased length with respect to the usual standard draft gear of 24½", while the standard overall dimension of 5' 6" from the center of the bolster to the face of the striking casting is maintained. The size of the springs and accordingly the spring capacity may also be increased by reducing the length of the back stop casting C. For instance, a gear some 55

8" longer than standard may be accommodated in this simple manner.

It is obvious that instead of the construction shown other types of yoke could be used and the 5 coupler and yoke could be connected in other manners, as by a known draft key. When such key is used, the sills should be cut away to permit the desired travel of the key, and clearance provided so that the draft key in pull will not go solid against the striking casting and prevent the 10 operation of the yoke projections.

The terms and expressions which I have employed are used as terms of description and not of limitation, and I have no intention, in the use 15 of such terms and expressions, of excluding any equivalents of the features shown and described or portions thereof, but recognize that various modifications are possible within the scope of the invention claimed.

20 What I claim is:

1. In a railway draft mechanism, a coupler, a yoke having upper and lower arms integrally connected at their rear ends, a connection between said yoke and coupler for causing the yoke to move 25 with the coupler in both draft and buff, car sills having front draft lugs secured thereto, a draft gear engaging said draft lugs and enclosed by said yoke, said draft lugs extending above and below said draft gear adjacent the connection between said yoke and coupler and into the planes of said yoke arms and lateral extensions on said yoke arms spaced normally a predetermined distance rearwardly of said draft lugs and movable in draft 30 into contact with said draft lugs to limit the pulling travel of said coupler.

2. In a railway draft mechanism, a pair of draft sills, means extending transversely of said sills at their forward ends, a coupler having a shank resting directly on said means, a yoke mov-

able with respect to said means and said sills and having upper and lower arms integrally connected at their rear ends, a connection between said yoke and coupler for causing the yoke to move with the coupler in both draft and buff, front draft lugs secured to said sills, a draft gear engaging said draft lugs and enclosed by said yoke, said draft lugs extending above and below said draft gear adjacent the connection between said yoke and coupler and into the planes of said yoke arms, and lateral extensions on said yoke arms spaced normally a predetermined distance rearwardly of said draft lugs and movable in draft into contact with said draft lugs to limit the pulling travel of said coupler.

3. In a railway draft mechanism, a coupler, a yoke having upper and lower arms integrally connected at their rear ends, a connection between said yoke and coupler for causing said yoke to move with said coupler in both draft and buff, car sills having front draft lugs secured thereto, a draft gear engaging said draft lugs and enclosed by said yoke, said draft lugs extending above and below said draft gear adjacent the connection between said yoke and coupler and into the planes of said yoke arms, and lateral extensions on said yoke arms spaced normally a predetermined distance rearwardly of said draft lugs and movable in draft into contact with said draft lugs to limit the pulling travel of said coupler and yoke to an extent less than the travel of the coupler and yoke in buff, said yoke having a greater cross sectional area between said lateral extensions and the connection with the coupler than rearwardly of said extensions for transmitting draft stresses to said sills in excess of those required to compress the gear a predetermined amount.

HUBERT L. SPENCE.
